[57] **ABSTRACT**

[21] Appl. No.: 126,967

A smoking product including a substantial proportion of tobacco stem material and incorporating carbamide and a saturated fatty acid composition having a carbon chain length of 16-18. The carbamide is present in an amount from 1.0 to 3.0 percent and the fatty acid is present in an amount of from 1.0 to 4.0 percent, by weight, of the stem material. The carbamide and fatty acid impart to the stem material, when it burns, some of the more pleasant taste and smell characteristics of burning tobacco leaf. The stem material may be in its natural state, but crushed, or it may be made into a reconstituted sheet or film.

**SMOKING PRODUCT WITH IMPROVED FLAVOR
AND METHOD OF MAKING IT**

This invention relates generally to tobacco, and has particular reference to making products having improved smoking qualities, and to a method of making such products.

The term "smoking products" is intended to include within its scope all known media, such as cigars, cigarettes, smoking tobacco, etc., for enjoying the aroma and flavor of burning tobacco.

The desirable flavor and smell of burning tobacco is derived primarily from the products of pyrolysis engendered by the smooth laminar portions of the leaves of the tobacco plant. The midribs of the leaves, commonly but inaccurately referred to in the trade as "stems", are deficient in producing the same effects. Burning stem portions produce a flat smoke and contribute only a lightly aromatic touch.

For the sake of simplicity, the smooth portions of the leaves will be referred to hereinafter as "leaf" and the midribs will be referred to as "stems."

Some tobacco products, notably sheeted tobacco

5 rated fatty acids and carbamide are non-toxic and harmless, and are compatible with tobacco and with substances commonly employed in the preparation of articles for smoking. For these reasons they have been found to be admirably suitable as additives to tobacco and tobacco products. Their employment is practically feasible, and allows tobacco stems to be used in larger proportions by making up for the natural deficiencies 10 of such stems as contributors to smoking values. Moreover, addition of the fatty acids and carbamide 15 beneficiates both the main and the side streams of smoking tobacco. By "main stream" reference is made to the smoke traveling directly into the smoker's mouth, and by "side stream" is meant the smoke emanating directly from the burning tobacco product.

A more particular object of the invention is to provide an economical and commercially practical procedure by means of which the fatty acid and carbamide can be advantageously incorporated in tobacco 20 products for the intended purpose.

The following flow diagram is illustrative of a procedure that has been found to be useful and satisfactory:

55 materials, contain appreciable and sometimes predominant proportions of natural tobacco stems. It is an object of this invention to improve the smoking qualities of such products. Coordinately, it is an objective of the invention to impart enhanced desirable aroma and flavor to articles for smoking whose composition includes, or may consist essentially of, fragments of natural tobacco stems.

The attainment of these objects, and such other objects and advantages as may be pointed out hereinafter, is predicated upon the discovery that adding moderate amounts of carbamide and a saturated fatty acid having a carbon chain length of 16-18 to stems unexpectedly imparts to them, when they are burned, some of the characteristic taste and smell of burning leaf. Thus, it helps to compensate for the taste-and aromagenerating shortcomings of the stems. Moreover, both the satu-

60 65 70 75 80 85 90 95
tobacco stems employed may be a by-product of tobacco processing. In any case this starting product need not be composed exclusively of stems but may include leaves or fragments of leaves in any desired proportion. The solvent employed to produce the extract, and leave a fibrous residue, is usually and preferably water but is not necessarily or exclusively aqueous. The beater employed is part of known papermaking equipment, and the fibrous residue is adequately comminuted so as to be employable like paper pulp in producing a slurry or suspension from which a paperlike web is produced in accordance with conventional papermaking techniques. The extract from the original product is first concentrated and may then be treated, if desired, in various ways (not shown) to alter or improve its composition. Finally it is introduced into the paperlike web, by any desired spraying or applicator or other suitable procedure, and the sheet is then dried.

The result is an artificial fibrous sheeted tobacco product which can be used in sheet form, or can be shredded and then used, in the ultimate production of articles for smoking.

The fatty acid and carbamide are preferably introduced, as indicated, either to the liquid concentrate prior to its application to the web, or to the web itself prior to the final drying procedure. However, other methods of incorporating these additives may be employed if desired. For introducing the additives, a soluble soap of the fatty acid can be made with potassium hydroxide, soda, or ammonium hydroxide in the usual way. The requisite carbamide may be combined in water solution with the fatty acid soap (potassium soap preferred). Alternatively, the fatty acid and carbamide can be dissolved in a volatile organic solvent, such as acetone.

The amount of the additives required to produce the desired beneficiating effect is relatively small. The addition of from 1.0 to 4 percent, by weight, of fatty acid and from 1.0 to 3.0 percent, by weight, of carbamide, to tobacco stems, in whatever form they may be employed, has proven satisfactory. Thus, in cases where the stems are made into a sheeted product, and where the fibrous part of the sheet is composed chiefly of such stems, the fatty acid is preferably introduced in an amount equal to from 1.0 to 4 percent of the sheet, by weight, and the carbamide is preferably introduced in an amount equal to from 1.0 to 3.0 percent of the sheet, by weight. If the fatty acid and carbamide are added in lesser amounts than mentioned above, the effect is unnoticeable. If a greater proportion of fatty acid than mentioned is employed, the smoke tends to take on a waxy note, and if a greater proportion of carbamide is used the smoke becomes ammoniacal.

In converting sheeted tobacco material containing fatty acid and carbamide to the form of an article for smoking, it may be combined in any desired proportion (and in sheet or shredded form) with natural tobacco. In some cases, it may be used entirely alone.

However, as is well known, the production of smoking tobacco and articles for smoking does not necessarily involve the employment of an artificial sheeted tobacco material of the character described. Whatever the form or nature of the tobacco product may be, if natural tobacco stem material is present in any amount, and if it is desired to compensate for its deficiencies as a creator of desirable pyrolysis products, saturated fatty acid and carbamide can be used as additives. Their manner of use can be varied, as may be desired, e.g., the carbamide and fatty acid soap solution could be sprayed onto or otherwise applied to tobacco leaves or into intermixture with a shredded tobacco product, or they could be used as an ingredient of other additives customarily employed. If reconstituted tobacco is being made by the cast film process, wherein powdered tobacco in a binder is extruded as a film and then dried, the carbamide and fatty acid soap solution may be mixed with the tobacco and binder prior to casting. The proportion of fatty acid and carbamide to be used are dependent in each case upon the amount of stems or stem derivatives present.

The mode of action of the fatty acid, for which palmitic acid is preferred, is in part that of supplying a material whose pyrolysis products apparently contribute a milder smoke flavor. The overall effect is best

when a commercially "pure" palmitic acid is used (100 percent saturated fatty acid, not over 10 percent C-18 present). Use of a larger percent of C-18 saturated fatty acid, or saturated fatty acid having a carbon chain length less than 16, leads to a waxy taste in the smoke when optimum amounts of the mixture are incorporated in the tobacco. The shorter chain fatty acids give an "off" flavor to the smoke when more than a trace is present and similarly the unsaturated fatty acids lead to undesirable flavors, particularly on storage for a time.

15 Carbamide does contribute some ammonia to the smoke which has the capability of reacting with some of the low molecular weight acids generated during combustion. Carbamide also has the capacity to reduce the concentration of aldehydes which are generated by combustion of cellulose and are suspected of being a major contributor to the extremely sharp and acrid smell of burning cellulose.

20 When used together, the fatty acid and carbamide show synergism, possibly since the ammonia incidentally released by pyrolyzing carbamide can react with acidic fragments formed from the fatty acid as well as from carbohydrates present. Whatever the mechanism, the smoke flavor has been found milder and preferable when addition of carbamide and fatty acid has been made to blends high in stems.

25 The preceding explanation is intended to suggest 30 ways in which the observed action can occur but is not intended to limit the disclosure to these precise reactions.

The following examples are illustrative:

EXAMPLE I

35 A mixture of lamina scrap, tobacco dust, and stems, consisting of approximately 75 percent stem and 25 percent leaf, was extracted with water in accordance 40 with the process described and the fibrous residue was beaten and formed into a paper-like sheet by ordinary papermaking techniques. Meanwhile, the extract was 45 concentrated by evaporation to about 45 percent solids, and to it was added controlled amounts of the fatty acid as a potassium soap and carbamide. The fatty acid employed was commercially available "extra pure" palmitic acid, which upon analysis was found to contain 95 percent palmitic acid (C-16) and 5 percent stearic acid (C-18). The extract with the additives was 50 introduced into the sheet by means of a size press. The amount of extract added was controlled so that the amount of extractables in the dried final product was about 50 percent, the concentration of the fatty acid being 3.35 percent, by weight, of the stem portion of 55 the reconstituted tobacco sheet, and the concentration of carbamide being 2 percent, by weight, of the stem portion of the reconstituted tobacco sheet.

60 As a control, reconstituted tobacco was made exactly as described above, except no fatty acid or carbamide were added to the extract.

Both sheets were shredded and made into cigarettes. When smoked by a panel of testers, cigarettes containing the additives were found to have excellent flavor, whereas cigarettes without the additives were harsh.

EXAMPLE II

Reconstituted tobacco was made according to the procedure described in Example I, except that "pure"

palmitic acid was used, having an analysis of 90 percent palmitic acid (C-16) and 10 percent stearic (C-18), in place of "extra pure" palmitic acid. Cigarettes made from this tobacco had excellent flavor, equal to that of the cigarettes of Example I.

EXAMPLE III

Reconstituted tobacco was made according to the procedure described in Example I, except that "food grade" palmitic acid was used, having an analysis of 70 percent palmitic acid (C-16), 25 percent stearic acid (C-18), and 5 percent other saturated fatty acids, in place of "extra pure" palmitic acid. Cigarettes made from this tobacco had flavor almost as good as the cigarettes of Examples I and II.

EXAMPLES IV - VI

Reconstituted tobaccos were made according to the procedure described in Example I, except that the fatty acids listed below were used in place of "extra pure" palmitic acid. Cigarettes made from the tobaccos were characterized as indicated on the following list:

Fatty Acid	Actual Analysis	Cigarette Quality
Stearic Acid	Stearic Acid C18-40%	Not quite as
"Double Pressed"	Palmitic Acid C 16-50%	Flavorful as
Tallow fatty acids	Other saturated fatty	Examples I and II
(not hydrogenated)	Stearic acid C18-28%	Slightly
	Palmitic acid C16-26%	disagreeable
	Other saturated	side stream
	fatty acids - 6%	odor and a
	Unsaturated oleic	faint waxy
	acid - 37%	note
	Other unsaturated	
	fatty acids - 3%	
"Pure" stearic acid	Stearic acid C18 - 65%	Flavor equal
	Palmitic acid C16-28%	to cigarettes
	Other saturated	of Example
	fatty acids - 7%	III

EXAMPLE VII

Natural tobacco fragments containing about 60 percent stems were powdered to such a degree that all passed through a 20 mesh (i.e., 20 openings per linear inch) screen and a substantial part through a 40 mesh screen. To 500 parts of a 2 percent solution of methyl cellulose, used as a binder, was added 0.7 parts carbamide and 0.9 parts potassium palmitate. One hundred parts of the powdered tobacco was mixed into the solution, producing a pasty dispersion. The latter was spread to form a film of such thickness that after drying in a stream of warm air to a moisture content of about 15 percent a dry film was obtained which approximated the thickness and weight of natural tobacco. The carbamide content of the film was 1.1 percent, by weight, of the stem portion, and the fatty acid content was 1.2 percent, by weight, of the stem portion.

The reconstituted sheet was shredded and made into cigarettes whose flavor and mildness were superior to cigarettes made from reconstituted tobacco made as described above but without the addition of carbamide and potassium palmitate.

EXAMPLE VIII

Crushed stems were sprayed with a solution containing carbamide and potassium palmitate such that 2 percent carbamide and 3.5 percent palmitic acid were deposited on the stems. Drying was done in a gentle stream of warm air and the volume of solution applied was such that no leaching occurred. The crushed stems were then blended with leaf shreds, the stems being 20

percent of the final mix. Cigarettes made from this blend were again preferred by the smoking panel over those made from the same blend using untreated crushed stems.

Obviously a similar result can be reached by spraying a carbamide-palmitic acid solution on the blended mix in Example VIII rather than on the stems alone.

A reconstituted sheet for use as a little cigar wrapper or a binder sheet for cigars can be made by the same 10 techniques outlined in Examples I-VII. In these cases, particularly in the little-cigar wrapper sheet, some wood fiber may be added to the tobacco sheet to strengthen it, but at the same time increasing the need for smoke flavor improvement. An illustration follows:

15

EXAMPLE IX

Following the procedure used in Example I with a mixture of cigar tobacco of which 70 percent was stem and 30 percent lamina, 20 percent un-bleached kraft pulp was added to the fibrous residue. To the concentrated extract was added enough palmitic acid soap and carbamide to give 1 percent palmitic acid and 4 percent carbamide, both percentages being by weight of the stems and kraft pulp portion of the reconstituted sheet. This sheet was tested by shredding and forming into cigarettes. All of the smokers preferred the cigarettes with the carbamide-palmitic additives to cigarettes which were identical except for the absence of the additives.

20

25

30

35

EXAMPLE X

Following the procedure of Example IX a product was made with only the 4 percent carbamide added. Evaluation of this indicated a mild but slightly ammoniacal, flavor.

EXAMPLE XI

Following the procedure of Example II but adding only 2.5 percent palmitic acid as the potassium soap to the reconstituted sheet gave a product that the smokers found better than the control but not as good as that of Example II.

The last two examples reflect the synergism present when fatty acid and carbamide are used.

The invention has been shown and described in preferred form only, and by way of example, and many variations may be made in the invention which will still be comprised within its spirit. It is understood, therefore, that the invention is not limited to any specific form or embodiment except insofar as such limitations are included in the appended claims.

What is claimed is:

1. A smoking product comprising a tobacco composition which includes a substantial proportion of tobacco stem material whose taste- and aroma-generating characteristics, when burned, are inferior to those of burning tobacco leaf lamina, said tobacco composition including carbamide and a saturated fatty acid composition having a carbon chain length of 16-18, said carbamide being present in an amount from 1.0 to 3.0 percent, by weight, of the stem material, and said fatty acid composition being present in an amount from 1.0 to 4.0 percent, by weight, of the stem material, said carbamide and fatty acid imparting to the stem material, when it burns, some of characteristic taste and smell of burning tobacco leaf lamina.
2. A smoking product as defined in claim 1 wherein said fatty acid composition is essentially palmitic acid.

3. A smoking product as defined in claim 1 wherein said tobacco composition also includes non-tobacco cellulosic material, said carbamide being present in an amount from 1.0 to 3.0 percent, by weight, of the combined stem and non-tobacco cellulosic material, and said fatty acid composition being present in an amount from 1.0 to 4.0 percent, by weight, of the combined stem and non-tobacco cellulosic material.

4. A smoking product as defined in claim 1 wherein said tobacco composition comprises an intermixture of natural tobacco and reconstituted tobacco.

5. A smoking product as defined in claim 1 wherein said tobacco composition is essentially natural tobacco.

6. A smoking product as defined in claim 1 wherein

said tobacco composition is essentially reconstituted tobacco.

7. A method of making a smoking product, comprising the steps of providing a tobacco composition which includes a substantial proportion of tobacco stem material, and combining with said stem material carbamide and a saturated fatty acid having a carbon chain length of 16-18, said carbamide being present in an amount from 1.0 to 3.0 percent, by weight, of the stem material, and said fatty acid being present in an amount from 1.0 to 4.0 percent, by weight, of the stem material, whereby said treated stem material, when it burns, has imparted to it some of the characteristic taste and smell of burning tobacco leaf lamina.
